Primary Examiner — Susan Moon Lee(74) *Attorney, Agent, or Firm* — Young & Thompson(57) **CLAIM**

The ornamental design for an RFID reader, as shown and described.

DESCRIPTION

FIG. 1 is a front, left side, and top perspective view of an RFID reader showing the new design;

FIG. 2 is a rear, right side, and top perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

1 Claim, 5 Drawing Sheets(56)
